(57) **CLAIM**

The ornamental design for a strapless bra, as shown and described.

DESCRIPTION

FIG. 1 is a bottom front perspective view of a strapless bra showing my new design;
 FIG. 2 is a top rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarged view of portion 9 shown in FIG. 1; and,
 FIG. 10 is an enlarged view of portion 10 shown in FIG. 7.
 The dot-dash circles and ovals depict the limits of the
 enlarged views and form no part of the claimed design.
